UNITED STATES PATENT OFFICE.

JOHN A. LAMONT, OF CHICAGO, ILLINOIS, ASSIGNOR TO AMERICAN STEEL FOUNDRIES, OF CHICAGO, ILLINOIS, A CORPORATION OF NEW JERSEY.

RAILWAY-CAR TRUCK.

1,377,702.

Specification of Letters Patent. Patented May 10, 1921.

Application filed November 8, 1920. Serial No. 422,462.

To all whom it may concern:

Be it known that I, JOHN A. LAMONT, a citizen of the United States, residing at Chicago, in the county of Cook and State of Illinois, have invented certain new and useful Improvements in Railway-Car Trucks, of which the following is a specification.

This invention relates to a railway car truck, and more particularly to a flexible connection between relatively movable truck side frame members in six-wheel trucks.

One object of the invention is to provide an improved flexible connection between the relatively rigid and flexible side frame members which will permit an increased freedom of movement.

Another object is to provide a simple and efficient pivotal connection between side frame members which also serves as means for securing a journal box to the side frame.

Another object is to provide simple and improved pivotal connection between relatively rigid and flexible side frame members adapted to meet the various requirements for successful commercial operation.

These and other objects are accomplished by means of the arrangement disclosed on the accompanying sheets of drawings in which—

Figure 1 is a fragmentary side elevation of a railway car truck embodying my invention;

Fig. 2 is a fragmentary top plan view of the same;

Fig. 3 is a sectional view taken in the plane of line 3—3 of Fig. 2; and

Fig. 4 is a fragmentary side elevation, parts being in section, of a railway car truck embodying a modification of my invention.

The various novel features of the invention will be apparent from the following description and drawings and will be particularly pointed out in the appended claims.

Referring to the figures of the drawings, it will be noted that my invention is disclosed in connection with an articulated truck side frame having a rigid side frame member 10 and a flexible side frame member 11, the latter having its inner end 12 extend into the inner forked end of the rigid side frame member and between the side flanges 13 thereof. The inner end of the flexible side frame member 11 terminates in a circular portion 14 which is received by a

socket portion 15 formed between the side walls of the rigid frame member 10, which arrangement permits of a relative vertical pivotal movement between the side frame members 10 and 11. The inner circular portion 14 of the flexible side frame member 11 is provided with a vertical opening 16 for the reception of a vertical pivot pin 17. In order that the relative vertical pivotal movement between the side frame members 10 and 11 is not interfered with, the opening 16 is tapered in such a manner that its smallest cross dimension is slightly larger than that of the diameter of the pin 17, the size of said opening increasing in both directions outwardly. In other words, the wall of the opening 16 is provided with a convex surface. This vertical pivot pin 17 also permits relative sidewise pivotal movement between the side frame members 10 and 11, the connection between the side frame members 10 and 11 thereby permitting a relatively horizontal and relatively vertical movement.

In the arrangement disclosed in Figs. 1 to 3 inclusive, the vertically arranged pivot pin 17 extends downwardly through an opening 18 in one of the laterally extending bracket portions 19 of the journal box 20, thereby acting as means for securing the journal box to the truck side frame, it being understood that a locking key 21 extends through the lower end of the pin 17 for preventing accidental withdrawal of said pin. The journal box has two laterally extending brackets 19 upon which a plurality of coil springs 22 and 23 rest, said coil springs being interposed between said journal box bracket portions 19 and portions of the truck side frame. It will be noted also that the vertical pivot pin 17 acts in a manner to position and retain the springs in a given position with respect to the journal box and side frame.

Referring to Fig. 4, it will be noted that I have shown a modification in which the vertically arranged pivot pin 24 passes only through the side frame members 10 and 11; in other words, it serves the sole function of forming a pivotal connection between the side frame members. It will be noted also that the point of pivotal connection between the side frames is an increased distance beyond the associated journal box.

There may be various other modifications, and it is my intention to cover all such modifications which do not involve a departure from the spirit and scope of the invention as set forth in the following claims.

I claim:

1. In a railway car truck, the combination of articulated side frame members, and a vertically arranged pivot pin passing through openings in said side frame members, one of said openings being formed to permit relative vertical movement between said side frame members.
2. In a railway car truck, the combination of articulated side frame members having openings, and a pivot pin extending through said openings, one of said openings being formed for permitting a relative pivotal movement of said side frame members in a plurality of directions.
3. In a railway car truck, articulated side frame members having coöperating curved portions to permit relative vertical movement between said side frame members, and a vertically arranged pivot pin extending through openings in said side frame members, one of said openings being formed to

permit relative vertical movement between said side frame members.

4. In a railway car truck, the combination of articulated side frame members one terminating in a rounded portion and the other having a socket portion for receiving said rounded portion for permitting relative pivotal movement in one direction, and a vertically arranged pivot pin extending through openings in said side frames for permitting relative lateral pivotal movement between said side frame members, one of said openings being formed to permit relative vertical pivotal movement between said side frame members.

5. In a railway car truck, the combination of articulated side frame members, a pivot pin extending through openings in said members, one of said openings being formed to permit a relative movement between said side frame members in a given direction, and a journal box secured to one of said side frame members by said pivot pin.

Signed at Chicago, Illinois, this 4th day of November, 1920.

JOHN A. LAMONT.
